(57) **CLAIM**

The ornamental design for a mounting apparatus, as shown and described.

DESCRIPTION

FIG. 1 is a perspective front view of a first embodiment of a mounting apparatus;

FIG. 2 is a front elevation view of the first embodiment thereof;

FIG. 3 is a rear elevation view of the first embodiment thereof;

FIG. 4 is a left side elevation view of the first embodiment thereof; the right side elevation view being a mirror image thereof;

FIG. 5 is a top elevation view of the first embodiment thereof; the bottom elevation view being a mirror image thereof;

FIG. 6 is a perspective front view of a second embodiment of a mounting apparatus;

FIG. 7 is a front elevation view of the second embodiment thereof;

FIG. 8 is a rear elevation view of the second embodiment thereof;

FIG. 9 is a left side elevation view of the second embodiment thereof; the right side elevation view being a mirror image thereof; and,

FIG. 10 is a top elevation view of the second embodiment thereof; the bottom elevation view being a mirror image thereof.

The broken lines shown in the drawings that illustrate portions of the mounting apparatus form no part of the claimed design.
